(57) **CLAIM**

I claim the ornamental design for a pair of bed rail stake pocket covers, as shown and described.

DESCRIPTION

FIG. 1 is a Top perspective view of a pair of bed rail stake pocket covers showing my new design.

FIG. 2 is a Top view thereof.

FIG. 3 is a Bottom view thereof.

FIG. 4 is a Long Side view thereof.

FIG. 5 is a Short Side elevational view thereof.

FIG. 6 is a Front view thereof; and,

FIG. 7 is a Back view thereof.
